UNITED STATES PATENT OFFICE.

STEPHEN J. CLULEE, OF ATTLEBORO, MASSACHUSETTS.

ART OF MAKING EYEGLASS-RIMS.

1,219,254.

Specification of Letters Patent. Patented Mar. 13, 1917.

Application filed August 16, 1916. Serial No. 115,148.

To all whom it may concern:

Be it known that I, STEPHEN J. CLULEE, a citizen of the United States, residing at Attleboro, county of Bristol, State of Massachusetts, have invented an Improvement 5 in the Art of Making Eyeglass-Rims, of which the following is a specification.

This invention relates to eyeglass rims, and more specifically to rims of the celluloid type. One of the objects thereof is to provide a practical and effective art of 10 making eyeglass rims, particularly of the above type. Other objects are to provide an art of the above nature which may be 15 inexpensively and quickly carried on. Other objects will be in part obvious and in part pointed out hereinafter.

The invention accordingly consists in the several steps and relation of such steps which 20 will be exemplified in the manner hereinafter described, and the scope of the application of which will be indicated in the following claims.

In the accompanying drawing, illustrative 25 of certain features of this invention,

Figures 1, 2, 3 and 4 are cross sectional views indicating various steps in the above art or process.

Figs. 5 and 6 are side elevations illustrating later steps in this art.

Fig. 7 is a side view of a rim.

Similar reference characters refer to similar parts throughout the several views of the drawing.

As conducive to a clearer understanding 35 of this invention, it may be noted that it deals with the rims of "eyeglasses", which term is broadly used to comprehend any device for mounting lenses before the eye, irrespective of whether such device is 40 mounted solely on the nose or is of the spectacle form. The invention moreover deals particularly with non-metallic or "celluloid" rims, the term "celluloid" also being 45 broadly used to denote any non-metallic substance suitable for use in connection with the art hereinafter described.

In the preferred method of carrying on 50 my art, the celluloid is forced into an elongated form, similar to wire, and having a rounded cross section. This may be done by extruding the celluloid while the latter is in suitably plastic condition through dies of the proper shape. Preferably the cross 55 section of the extruded material is not exactly round but is provided with a slight

depression running lengthwise along one side as indicated at 1 in Fig. 1 of the drawing. With the celluloid in proper condition for working, the groove or lengthwise recess in the material or celluloid wire is preferably deepened to the form shown at 2 in Fig. 2 of the drawing. This may be done by milling or by other mechanical means. It is to be understood of course that many 60 of the advantages of this invention may be achieved either by milling the groove to its entire depth instead of first forming it by extrusion, or by extruding the material with a groove down to the form shown in Fig. 2 65 of the drawing.

In the preferred method of carrying on my art, the celluloid is hardened after extrusion and there is then inserted a metallic wire 3 which is fitted snugly at the bottom 70 of the recess 2 and runs through the entire length of the celluloid wire 4. The material is then run through suitable rolls by which the celluloid is forced into a properly uniform cross section of the desired contour. 75 This action, moreover, embeds the metallic wire 3 with the celluloid projecting thereover, as indicated at 5, and locking the metal wire in position. It is to be understood that this rolling step is preferably 80 employed even though no metallic wire is 85 inserted.

The entire material is then wound on a mandrel, being closely wound thereon and being disposed with the groove or recess 6 90 on the outer side, as indicated in Fig. 5 of the drawing. The ends being suitably secured in temporary position, the mandrel 7 is then rotated and the material quickly 95 and thoroughly polished along its entire exposed surface. The material is then removed and re-wound upon the mandrel with its outer or non-grooved side exposed. The material is again polished while in this condition and thus its entire surface, both inside and outside, is given a thorough and careful finish. While on the mandrel 7 in this last position, as indicated in Fig. 6, the material is heated to a suitable degree, in the neighborhood of one hundred degrees 100 Fahrenheit, and thereupon permitted to cool, whereby it tends to set or retain the form which it then has. The entire coil of celluloid wire, which may extend throughout a considerable length and comprise a 105 great number of turns, is then cut or slit longitudinally of the mandrel, as indicated

by the line 8—8, this acting to sever the coils into a number of separate rims which are readily slipped off the end of the mandrel.

5 In the final form of the rims shown in Fig. 7 of the drawing, each rim is a complete circle cut through at the point 9 and each is of uniform cross section throughout and accurately rolled to size. Moreover, a thorough polish or finish is given to the entire device, both inside and outside, and it possesses a high degree of mechanical strength and even without the embedded metallic wire, its method of manufacture tends to 10 render it most homogeneous and tough. The metallic wire, moreover, securely locked in position and embraced by the celluloid, gives it the highest degree of mechanical strength. It is to be understood that if desired, the recess, as shown in Fig. 2 of the drawing, may be polished by the step indicated in Fig. 5 before the metallic wire is inserted.

It will be seen that a rim formed as above not only possesses the above advantages but is readily manipulated in use, as the lens may be quickly inserted by springing the rim apart at the cut 9. The rim tends to snap into closed position due largely to its method of manufacture, for it possesses a 25 higher degree of elasticity than if merely cut from a blank. It will thus be seen that there is provided an art in which the several objects of this invention are achieved.

As the art herein described might be carried on with apparent variations, it is to be understood that all matter herein set forth or shown in the accompanying drawing is to be interpreted as illustrative and not in a 35 limiting sense.

40 I claim as my invention:

1. An art of the character described which comprises forming an elongated member from celluloid in plastic condition, permitting said member to harden, winding said member into a coil, heating said member and permitting it to cool, and cutting said coil throughout the several turns thereof.

2. An art of the character described which comprises forming an elongated member from celluloid in plastic condition, rolling said member in a form with a groove extending lengthwise thereof, winding said member into a circular coil, and cutting said member across the several turns of said coil.

55 3. An art of the character described which comprises forming an elongated member from celluloid in plastic condition with a groove extending lengthwise thereof, permitting said member to harden, winding said member about a mandrel, heating said member and permitting it to cool upon said mandrel, and cutting said member on said mandrel into separate rims.

60 4. An art of the character described which comprises forming an elongated member

from celluloid with a groove extending lengthwise thereof, rolling said member into the desired cross section, winding said member into a coil, and cutting said member across the turns of said coil.

70 5. An art of the character described which comprises forming a wire from celluloid, milling the groove longitudinally of said wire, winding said wire into a coil, and cutting said wire crosswise of the turns of 75 said coil.

6. An art of the character described which comprises forming an elongated member with a groove therein, inserting a metallic wire within said groove extending lengthwise of said member, winding said member with said wire on a mandrel, and cutting said member and said wire transversely of the planes of its turns.

80 7. An art of the character described which comprises forming an elongated circular wire with a groove extending lengthwise thereof, inserting a metallic wire within said groove, winding said celluloid with said inserted wire upon a mandrel with the groove 90 on the side toward the mandrel, and cutting said wire in a direction lengthwise of the mandrel.

85 8. An art of the character described which comprises forming an elongated member from celluloid with a longitudinal groove therein, inserting a metallic wire within said groove, and rolling said celluloid member to force said metallic wire into interlocking relation therewith.

9. An art of the character described which comprises forming a wire from celluloid with a longitudinal groove therein, winding said member upon a mandrel with the grooved side upward, and polishing the 100 exposed grooved surface of said member upon said mandrel.

10. An art of the character described which comprises forming an elongated member from celluloid, winding said member into a coil with one side out, polishing the outer side of said member, rewinding said member with the opposite side up, and cutting said member throughout the several turns of the coil.

115 11. An art of the character described which comprises forming an elongated member from celluloid in plastic condition with a groove extending longitudinally thereof, permitting said member to harden, 120 rolling said member into the cross section, winding said member upon a mandrel, heating said member and permitting it to cool upon said mandrel, and cutting said member transversely of its turns.

12. An art of the character described which comprises forming an elongated member from celluloid in plastic condition with a groove extending lengthwise thereof, embedding the wire within said groove, 130

winding said member with said wire upon a mandrel, heating said member and permitting it to cool, and cutting said member with said wire transversely of its turns.

6 13. An art of the character described which comprises extruding celluloid in plastic form into a longitudinally grooved wire, winding said wire upon a mandrel with the grooved side outward, and polishing the exposed grooved surface of said wire.

10 14. An art of the character described which comprises extruding celluloid in plastic condition into a wire, winding said wire upon a mandrel with one side outermost, polishing the exposed surface of said wire upon said mandrel, rewinding said wire with the opposite side outermost, polishing the exposed surface thereof, and cutting it on said mandrel into separate rims.

20 15. An art of the character described which comprises forming a wire from celluloid, rolling said wire into the desired cross section with a groove extending lengthwise thereof, winding said wire upon a mandrel with the grooved side outermost, and polishing the exposed surface of said wire.

30 16. An art of the character described which comprises forming a wire from celluloid, rolling said wire into the desired cross section, winding said wire upon a mandrel with one surface exposed, polishing said surface, re-winding said member upon a mandrel with the opposite side exposed, polishing said exposed side, and cutting said wire into separate rims.

35 17. An art of the character described which comprises forming a wire from celluloid with a groove extending longitudinally thereof, winding said wire upon a

mandrel with the grooved side outward, polishing said outward grooved surface, re-winding said wire upon a mandrel with the opposite side exposed, polishing said exposed surface, and cutting said wire lengthwise of the coiled end on which it is wound.

18. An art of the character described which comprises extruding celluloid in plastic condition into a wire, rolling said wire into the desired cross section with a groove 50 extending longitudinally thereof, winding said wire into a coil with the grooved side outermost, and polishing the exposed grooved side.

19. An art of the character described which comprises extruding celluloid in plastic condition into a wire, rolling said wire into the desired cross section with a groove 55 extending longitudinally thereof, winding said wire into a coil with the grooved side outermost, polishing the exposed grooved side, rewinding said wire with the opposite side exposed, polishing said last exposed side, and cutting said wire into separate rims.

20. An art of the character described which comprises forming a wire from celluloid with a groove extending longitudinally thereof, rolling said wire into the desired cross section, winding said wire upon 70 a mandrel with the grooved side outward, polishing the exposed surface, rewinding said wire with the opposite side outermost, polishing the exposed surface, and cutting said wire upon said mandrel into separate 75 rims.

In testimony whereof, I have signed my name to this specification this ninth day of August, 1916.

STEPHEN J. CLULEE.
